UNITED STATES PATENT OFFICE.

FRANK G. FARNHAM, OF WHITE MILLS, ASSIGNOR TO HIMSELF AND
MARCUS M. TREADWELL, OF HAWLEY, PENNSYLVANIA.

PERMUTATION-LOCK.

SPECIFICATION forming part of Letters Patent No. 238,666, dated March 8, 1881.

Application filed August 26, 1880. (Model.)

To all whom it may concern:

Be it known that I, FRANK G. FARNHAM, of White Mills, in the county of Wayne and State of Pennsylvania, have invented certain new and useful Improvements in Permutation-Locks; and I do hereby declare that the following is a full, clear, and exact description of the invention, which will enable others skilled in the art to which it appertains to make and use the same, reference being had to the accompanying drawings, which form a part of this specification.

My invention relates to an improvement in permutation-locks, more especially designed for use on drawers, though applicable to boxes and doors; and its object is to furnish a simply constructed and easily operated permutation-lock of neat design and ornamental appearance.

20 In an application for a patent now pending in the United States Patent Office I described a form of lock wherein the changes in the combination were effected by altering the position of springs inclosed in internally-notched rings, so as to allow a toothed bar to pass through only a single notch of a series, and thereby operate a bolt. My present improvement operates on substantially the same principle, but differs from the former in various particulars 25 of construction, which, with their manner of operation, will be now more fully described and hereinafter claimed.

In the drawings, Figure 1 is a perspective of the lock applied to a drawer; Fig. 2, a central longitudinal section; Fig. 3, a view of the sliding cylinder; Fig. 4, a plan view of the bolt mechanism; Fig. 5, a plan of the box and barrel; Fig. 6, a separate view of the device for changing the combination, and Fig. 7 a 40 separate view of one of the holding-rings.

In these drawings, A represents a plate of sheet metal adapted to be secured to the drawer or door by screws. It has on one side an upturned edge, a, perforated to allow the bolt to pass, and having in the center a perforation, a'.

To the plate is securely attached, by rivets or in any other proper manner, a circular box or case, B, which contains the working parts, 50 and has perforations b c on opposite sides to give passage to the bolt.

Within the box or case B is mounted a frame, which consists of a barrel, d, and two standards, e e, each provided with a threaded opening, e'. The barrel is slotted on one side, 55 as at f, and on the other has a groove, g, its upper end being screw-threaded a short distance, as shown. The frame is secured in the box or case B by screws passing through two of the four openings in the latter.

D is a cylinder of a diameter to fit closely within the bore of the barrel d in which it is intended to reciprocate. It is provided on one side with a series of pins, i, of sufficient size to work easily in the slot f in the barrel. The 65 cylinder D is bored out centrally to receive the spindle of a key, E, which turns freely therein, and is attached to, or formed integral with, a head, j, and turning-plate k, the latter having a milled edge, and the former bearing 70 on the end of the cylinder D, its diameter being equal to that of such cylinder. The key-bit l is of any desired form to operate the bolt. The cylinder D and key E are inserted in the barrel, the bit and pins sliding in the 75 slot f, the cylindrical end of the key-spindle passing through the perforation a' in the plate A, and a spring, m, forcing the key and rod outward.

The key, when the parts are held in their 80 normal position by the spring m, can be turned freely in either direction, the bit bearing on the lower end of the barrel, and sliding past the bolt, which is represented as a whole by F and shown in Fig. 4. This bolt is intended 85 more especially for drawer and box rims, and consists of a plate, o, having a curved central cut-away portion, in which the key-bit works. It is provided with an ordinary catch, n, working through the slot in the flange a, and with 90 a stop, o'. A raised arm or flange, p, of angular shape, as shown, forms a surface against which the key-bit bears in operating the bolt. The other end of the shank of the bolt passes through a slot, c, in the box or case, and a 95 spring, q, holds it in position and prevents it from dropping down.

In order that the device may be used in connection with bolts working to the right or left, or up or down, four screw-holes, h, are provided in the sides of the box.

When the parts are in place, for convenience

in setting up and reading the combinations the slot *f* in the barrel is always placed upward, and this rule being observed the plate *A* may be turned, so as to bring the bolt in line and cause it to slide in either direction, the standards *e* being always at an angle of forty-five degrees to the movement of the bolt, and the slotted side of the barrel being always upward.

10 For use in connection with doors where a snap-catch is desired the construction would be modified, though not materially. Some change in the form of the bolt would be made to adapt it to receive a spring; but such modifications are within the scope of my invention.

15 Since when the parts are in their normal position the key-bit passes over the arm *p* when revolved, it is evident that such bit must be forced in, so as to bring it in contact with the said arm. In order to prevent and regulate this movement of the key I provide a series of rings, carried by the barrel, by which any number of combinations can be formed and changed 20 at will. These rings operate on the principle of those shown in my application referred to; but their construction is different, and specially adapted to this form of lock.

25 *G* represents rings denominated "working rings," illustrated in Figs. 2 and 6. They are beveled, as shown, and provided with a milled edge to enable them to be turned freely. The working-rings form a series, diminishing in diameter from the base of the barrel, in order 30 that the lower ring may be easily seized and turned by the fingers. Each ring is provided with a flange, *q*', as shown, and is internally notched, and marked on the outside, opposite each notch, with an appropriate symbol. Between these rings, and fitting in the hollowed 35 portion surrounded by the flange *q*', are holding-rings *H*, of plain exterior, but provided on the interior periphery with a stud, *r*, and a notch, *s*, placed opposite one another. The 40 stud enters the groove *g* in the barrel, while the notch permits the pins on the rod *D* to pass freely. The flanged and hollow form of the working-rings allows the holding-rings to be entirely inclosed, and forms an exceedingly 45 compact construction. The rings *H* are held stationary on the barrel, the rings *G* revolving freely.

50 The device for changing the combination consists, as in my former application, of a spring inclosed by the working-rings, having its ends bent and inserted in one of the notches in such ring, thus allowing the pins on the rod *D* to pass through that particular notch; and as two or more rings are used it is evident 55 that the notches on all the rings in which the

ends of the springs are placed must be in line to permit the rod to be moved, and that by means of the symbols placed opposite the notches their position may be regulated at will.

60 *I* is a cap, which is screwed onto the end of the barrel and secured by a screw or rivet. It is provided with a small recess, *t*, in which the last of the series of pins on the part *D* enters and prevents it from being unscrewed.

65 The operation of my lock is as follows, the combination being set on figures 1 4 1: The rings are turned until the figures 1 4 1 are brought in line with the arrow on the cap *I*. The plate or handle is then pushed in, which brings the key-bit in position to bear on the arm *p* and throw the bolt. The spring then throws the key and cylinder *D* back, and the combination is broken by turning the rings. It is then impossible to push the key in, though it 70 may be revolved freely in either direction. 80

75 The lock will be finished in a neat and ornamental design, and will be of very attractive appearance. The main advantages, however, lie in its exceeding simplicity of construction and the ease with which it is operated. 85

Having thus described my invention, what I claim as new is—

1. The combination of the barrel *d*, carrying the internally-notched rings *G*, a sliding cylinder, *D*, having pins, and a key, carried by 90 such sliding cylinder, and adapted to revolve independently of said cylinder, and thereby operate the bolt.

2. The combination of a sliding bolt, a key to operate such bolt, a cylinder, *D*, provided 95 with pins, and a series of internally-notched rings provided with springs.

3. The box or case *B*, having screw-holes *h*, in combination with the barrel *d*, having standards *e*, provided with screw-holes *e'*, whereby 100 the relative position of the barrel and box may be changed, so that the movement of the bolt may be either vertical or horizontal.

4. The described permutation-lock, consisting of a box or case, a slotted barrel, *B*, carrying internally-notched rings, a sliding cylinder having pins, a key carried by such sliding cylinder, and a bolt, whereby the setting up of the combination permits the cylinder carrying the key to be moved longitudinally and the 105 key to operate the bolt by an independent rotary motion.

110 In testimony that I claim the foregoing as my own I have hereto affixed my signature in presence of two witnesses.

FRANK G. FARNHAM.
